UNITED STATES PATENT OFFICE.

JOHN CHESNEY, OF PAULSBORO, NEW JERSEY, ASSIGNOR TO E. I. DU PONT DE NEMOURS AND COMPANY, OF WILMINGTON, DELAWARE, A CORPORATION OF DELAWARE.

SHELL DRILL.

Application filed June 12, 1916. Serial No. 103,134.

To all whom it may concern:

Be it known that I, JOHN CHESNEY, a citizen of the United States, of Paulsboro, in the county of Gloucester and in the State of New Jersey, have invented a certain new and useful Improvement in Shell Drills, and do hereby declare that the following is a full, clear, and exact description thereof.

My invention relates particularly to an apparatus designed for drilling holes in charges for shells, such as explosive charges in the same.

The object of my invention is to provide an apparatus of this character by means of which shell charges may be drilled and in such a manner that danger of explosion due to friction from accumulated borings is avoided, and in such a manner that the drilling is carried out expeditiously and with a minimum amount of labor.

While my invention is capable of embodiment in many different forms, for the purpose of illustration I shall show only one form thereof in the accompanying drawings, in which,

Figure 1 is a vertical section of an apparatus made in accordance with my invention and,

Fig. 2 is a plan view of a supporting clip for the shell.

Fig. 3 is a sectional view showing the shell in operative relation to the drill and adjacent parts of the apparatus.

In the drawings I have shown a base 1, having a bearing 2 for supporting a vertical shaft 3, which carries a bevel gear 4, meshing with a bevel gear 5 on a stud shaft 6, located in a bearing 7 in a casing 8, supported from the base 1, and driven from any suitable source of power. A chute 9 passes downwardly in an inclined direction and outwardly through the casing 8 so as to discharge the borings from the drill. The shaft 3 carries a tap arm 10 adjustably mounted on a screw 11, for the purpose of jarring the chute 9 each time the shaft rotates. At its upper end the shaft 3 passes through a sleeve 12 supported in a recess on the top of the casing 8. A suitable housing 13 rests on top of the sleeve 12. At its upper end the shaft 3 is connected to a tool holder 14 by means of a screw 15. Said tool holder 14 on its side has a leather wiper 16 which is attached thereto by one or more

screws 17, said wiper being provided to discharge the borings downwardly through the chute 11. The tool holder 14 carries a tool 18 with horizontally-directed blades to produce a countersink in the charge in the shell, and above the tool 18 the tool holder carries a drill 19 which is secured in the holder 14 by a screw thread 20 on the drill or parts attached thereto. The housing 13 has at one side a recess 21 for receiving a pivoted adjustable stop 22 located in a bearing 23 screw-threaded to the housing 13 and having screw-threaded thereto collars 24 for adjusting the vertical position of the stop 22. Said housing 13, furthermore, has a pair of diametrically opposed slots 25 designed to receive the ends of two bent strips of metal 26 and 27 having their ends connected together by rivets 28 to form arms 29 and 30 and their central portions bent into curved positions to form a circle 31 for receiving and supporting an inverted shell carrying an explosive charge of any suitable character as for example of trinitrotoluene. The arms 29 and 30 slide in the slots 25 and the housing 13 has an enlarged bore 32 at its upper end to accommodate the circular portion 31. The arms 29 and 30, outside of the housing 13, rest upon bars 33 which are attached to a cylinder 34 adapted to move upwardly and downwardly by air pressure and carrying at its upper end a horizontal extension 35 having a downwardly extended bar 36 to rest upon the top of the shell, and a laterally-directed handle 37 to permit the bar 36 to be swung away from its position above the housing 13. At its side the cylinder 34 is connected in any suitable manner with a source of air supply, as for example, a pipe 38 which may have any suitable connection to the cylinder 34. A three-way cock 40, in the pipe 38, permits the alternate supply and exhaust of the air to and from the cylinder 34. On the base 1 there is a stud piston 41 against which the cylinder 34 acts in being raised and lowered. A door 42 is provided at the side of the casing 8.

In the operation of my invention, it will be assumed that the cylinder 34 has been moved upwardly by a supply of air from the pipe 38 through the operation of the valve 40 until the bars 36 and 33 have cleared the top of the housing 13 and that the handle 37 has been operated to move the bar 36 to

one side. The shell is then inserted in the circle 31 and the arms 29 and 30 attached thereto carrying the shell are placed on the bars 33. The shell thus supported is then 5 swung over the open upper end of the housing 13 until the shell registers therewith and the arms 29 and 30 register with the slots 25. Thereupon the air is gradually exhausted from the cylinder 34 by operating 10 the valve 40 and the shell lowered by the aid of its weight and the weight of the bar 36 and attached parts until the end of the shell or parts attached thereto rest against the stop 22. While the shell is being 15 lowered in this manner the drill 19 and the tool 18 will be rotated by the gears 4 and 5 so as to produce a deep hole in the center of the charge contained in the shell and a counter-sunk hole of larger diameter adjacent thereto and at the mouth of the deep 20 hole. The holes thus provided permit the insertion of primers of any desired character for exploding the shell at a suitable time, as for example, when the shell strikes 25 the object at which it has been fired. While the boring is taking place the wiper 16 continually removes the borings of the explosive material from contact with the rotating parts and discharges the same downwardly 30 and outwardly by means of the chute 11.

While I have described my invention above in detail, I wish it to be understood that many changes may be made therein without departing from the spirit of my invention as defined in the claims.

I claim:

1. A drilling apparatus for shells having a drill, and means to feed a shell downwardly in an inverted position to the drill, 40 a reciprocable carrier for the shell and means for imposing fluid pressure upon said carrier to elevate the same.

2. A drilling apparatus for shells having

a drill, and means to feed a shell downwardly in an inverted position to the drill, 45 comprising a swinging carrier for the shell.

3. A drilling apparatus for shells having a drill, and means to feed a shell downwardly in an inverted position to the drill, 50 comprising a swinging carrier for the shell having a supporting arm and a shell clip engaging therewith.

4. A drilling apparatus for shells having a drill, a housing for the same, and means to feed a shell downwardly in an inverted 55 position to the drill, comprising a swinging carrier for the shell, having a supporting arm and a shell clip engaging therewith, said shell clip having an arm which extends through a slot in the drill housing. 60

5. A drilling apparatus for shells having a drill, a discharge chute for borings and a wiper for feeding the borings to the chute.

6. A drilling apparatus for shells having a vertical inverted drill, a discharge chute 65 for borings and a wiper for feeding the borings to the chute.

7. A drilling apparatus for shells having a drill, a discharge chute for borings and a horizontally moving wiper for feeding the 70 borings to the chute.

8. A drilling apparatus for shells having a vertical inverted drill, a discharge chute for borings and a horizontally moving wiper for feeding the borings to the chute. 75

9. A drilling apparatus for shells comprising an inverted drill, a stationary housing aligned therewith adapted to engage a shell to align it with the drill, and movable means for supporting a shell within said 80 housing to control the position of the same with reference to the drill.

In testimony that I claim the foregoing I have hereunto set my hand.

JOHN CHESNEY.
